ELECTRIC SWITCH.

1,327,640.

Specification of Letters Patent. Patented Jan. 13, 1920.

Application filed August 14, 1918. Serial No. 249,758.

To all whom it may concern:

Be it known that I, CLARENCE C. STIRLING, a citizen of the United States, residing at Hartford, in the county of Hartford and 5 State of Connecticut, have invented certain new and useful Improvements in Electric Switches, of which the following is a specification.

This invention relates to electric switches. 10 While it is conceivable that the device may be incorporated in switches of various kinds, they are of particular utility when associated with one of the pendent snap type. I provide a structure which is exceedingly 15 simple, which can be readily made and the parts of which can be quickly assembled, the action being positive and certain.

In the drawings accompanying and forming part of the present specification I have 20 shown in detail a form of embodiment of the invention which to enable those skilled in the art to practise the same will be set forth fully in the following description. I do not necessarily limit myself to this particular construction; I may depart therefrom in several respects within the scope of the invention defined by the claims following said description.

Referring to said drawings:

30 Figure 1 is a vertical side elevation of a switch involving the invention.

Fig. 2 is a vertical section on the line 2—2 of Fig. 1, looking in the direction of the arrow.

35 Fig. 3 is a transverse section on the line 3—3 of Fig. 2.

Like characters refer to like parts throughout the several views.

The switch includes in its make-up a suitable body such for instance as that denoted 40 in a general way by 2 and made of some convenient insulating material such as usually found in pendent switches. As shown the body has in its under portion the chamber or cavity 3, open in its under side or bottom. Besides this there is in said body 45 the slot 4, the lower portion of which intersects the chamber or cavity 3, and the top of which is in the plane of the upper surface 50 of the body 2. The body 2 is surrounded by a casing or housing such as 5, generally of sheet metal and in two sections separably connected by a slip or other joint for instance as found in pendent snap switches. 55 The casing or shell 5 extends a short dis-

tance above the body 2 and has a practically central opening in which is fitted an insulating ring or bushing as 6 through which pass the wires 7 and 8, the bared ends of which are connected with terminals in the housing. 60 One terminal or contact is such a one as that denoted in a general way by 9. The shank of this terminal lies in a groove or channel as 10 in one wall of the slot or opening 4, said shank terminating at its upper end in 65 a bend or off-set 11 fitted in an aperture 12 cutting the groove or channel 10. The off-set 11 is in turn provided with a pendent portion 13 embedded in a seat 14 in the body 2. Tapped through the off-set 11 is the 70 screw 15 around which may be passed the bared portion of the conductor 7. The body of the terminal or contact 9 is deflected outwardly between its ends the angular portion of said body fitting against the correspondingly shaped outer surface of the channel or groove 10. The free end of the said terminal or contact 9 is practically against an outer surface of the chamber or cavity 3 and is also in proximity to an actuator 75 hereinafter more particularly described. There is molded into the upper side of the body 2 the metal or other conducting plug as 16 which is threaded to receive the screw 17 around which is passed the bared end of 80 the conductor or wire 8, the head of said screw 17 serving to force the wire against the metal plug 16. This metal plug 16 has a transverse bore 18 in register with a cylindrical opening 19 extending entirely across 90 the body 2, the two parts of the opening 19 and the opening 18 receiving as shown for rocking or oscillating motion, the pin 20 of metal or other conducting material.

The actuator for the switch may be of 95 any desirable character, that denoted in a general way by 21 meeting my conditions in a proper manner. As shown this actuator consists of a portion as 22 provided with a manipulating portion or button 23 and 100 a second portion as 24 furnished with a button as 25 of insulating material, complementary to the button 23. The part of the actuator between the two buttons extends through registering holes in the body 2 and 105 casing 5, the buttons being obviously exterior of the casing so as to be operated when occasion requires. The portion 24 is of metal or other conducting material excepting of course, the button 25 which is of some 110

suitable insulating substance. It has at its inner end the threaded portion 26 fitted in a central socket in the end of the insulating portion 22 which in the present case extends unbrokenly from the portion or section 24 to and including the button 23. In the insulating part of the actuator such as between the ends of the section or portion 22 is an annular groove as 27; while a similar groove as 28 is formed in the conducting portion or section 24.

The circuit controller or switching member may like the other parts within certain limits vary. That shown is denoted in a general way by 29. It involves at its lower end a loop 30 through which passes the actuator 21 between the two buttons 23 and 25. The side branches of the loop 30 are continued upwardly as at 31 and 32, these branches crossing and terminating in prolongations or arms 33 and 34 parallel with each other and which project near their free ends freely through openings in the pivot or pin 20. While the snap movement may be secured in any desirable way the coiled spring 35 answers satisfactorily in this connection, the upper terminal of the spring having an eye 36 fitting a circumferential groove as 37 in the pin or pivot 20 between the arms 33 and 34. The lower terminal of the spring has an eye 39 which embraces the prolongations 31 and 32 where they cross.

The grooves 27 and 28 to which I have referred constitute a suitable retaining or detent means to positively hold the switching member 29 in its respective positions. The parts are shown as occupying the open position by full lines in Fig. 1, the loop or bend 30 at this time being disposed within the groove 27. It will be supposed that it is desired to close the circuit. In this event the following procedure may be adopted: The actuator 21 will be moved toward the left or the dotted line position in said view, the switching or circuit controlling member 29 being carried therewith and the pivot 20 at the same time being rocked and obviously the spring 35 being stretched. The motion will continue until the loop 30 strikes the right wall of the chamber or socket 5, so that on a slight further movement toward the right in said Fig. 1 of said actuator 21, the loop 30 will be slipped out of the groove 27 and thus be automatically disengaged from the restraining effect of the detent or holding groove 27. As soon as this particular condition ensues, the power of the stretched spring will come into action and then snap said switching member 29 from the dotted to the full line position in Fig. 1, so that the loop 30 will be projected into the groove or channel 28 which it will be remembered is in conducting material. In this event the circuit will be closed through the wire 7, contact or terminal 9, metal portion 24, circuit

controlling or switching member 29, pivot 20, plug 16, and wire 8. To open the circuit the button 23 on the right then in the dotted position, will be moved toward the left, thus carrying the circuit controller or switching member 29 and spring therewith as the pivot 20 rocks; the motion continuing until the switching member strikes the left wall of the chamber or cavity 3 at which point on the slight further advance of the actuator toward the left the switching member 29 will be dislodged from the groove 28 and snapped into the groove 27.

I desire to call attention to certain points. It will be noticed that the actuator or push rod 21 is partly of conducting material and partly of insulating material. Associated with this actuator is a switching member, contactor or contact maker which in a certain relation as I have already explained makes contact with the conducting part of the actuator. I also deem it desirable to call attention to the fact that the spring by which the necessary snap movement is obtained is always in parallelism with the switching member or swinging contactor, this switching member or contactor, although it does have a rocking or swinging motion, really slides, the sliding action as a matter of fact effecting the swinging motion. 95

What I claim is:

1. A switch comprising an actuator having insulating and conducting portions, a movable switching member having a dislodgable connection with the actuator, the actuator on its movement carrying the switching member therewith, a fixed part against which the switching member is abutted on the movement of the actuator, the latter having a further movement beyond the point at which the switching member engages the fixed part, and spring means conditioned by the actuator on each of its movements for shifting the switching member when it is freed from the actuator on said opposite movements into alternate engagement with the insulating and conducting portions of the actuator. 105

2. A switch comprising an actuator having insulating and conducting portions, a supporting body which carries the actuator, a swinging switching member having a dislodgable connection with the actuator, the actuator on its movement carrying the switching member therewith and against a relatively fixed part of the body, whereby on the continued movement of the actuator the switching member will be freed from the actuator, and spring means swinging with the switching member when moved by the actuator, to impart a continued movement to the switching member when the same is freed by the actuator. 115 120 125

3. A switch comprising an actuator having insulating and conducting portions, a

- supporting body which carries the actuator, a swinging switching member having a dislodgable connection with the actuator, the actuator on its movement carrying the switching member therewith and against a relatively fixed part of the body, whereby on the continued movement of the actuator the switching member will be freed from the actuator, and a spring movable with the switching member and conditioned by the movement of the actuator to shift the switching member when it is freed from the actuator to cause the switching member to engage the insulating and conducting portions in alternation.
4. A switch comprising a back and forth movable actuator having insulating and conducting portions, a supporting body which carries the actuator, a swinging switching member having dislodgable connections with the actuator on opposite movements thereof, the actuator on each movement of the switching member carrying the switching member therewith and against the body, whereby on the continued movement of the actuator in each direction the switching member will be freed from the actuator, and spring means conditioned by the actuator on each of its movements for shifting the switching member when it is freed from the actuator on said opposite movements into engagement alternately with said insulating and conducting portions.
5. A switch comprising an actuator having insulating and conducting portions, a swinging switching member having a dislodgable connection with the actuator, the actuator on its movement carrying the switching member therewith, a fixed part against which the switching member is abutted on the movement of the actuator, the latter having a further movement beyond the point at which the switching member engages the fixed part, and spring means to swing with the switching member and conditioned to impart a snap movement to said switching member when the same is dislodged from the actuator and to engage insulating and conducting portions in alternation.
6. A switch comprising a reciprocating push rod, constituting an actuator partly of conducting material and partly of insulating material, a swinging switching member movable by the push rod, and spring means conditioned by the push rod for imparting a snap movement to the switching member to move the same alternately into engagement with the conducting and insulating portions of the push rod.
7. A switch comprising a switching member mounted for swinging and slidable movements, a spring tending constantly to produce the sliding movement and the sliding movement in turn producing the swinging
- movement, and an actuator having insulating and conducting portions for conditioning the spring to impart a snap movement to the switching member and thus cause the latter alternately to engage said insulating and conducting portions.
8. A switch comprising an actuator in the form of a push rod, partly of conducting material and partly of insulating material, a switching member having a dislodgable connection with the actuator, the actuator on each of its movements carrying the switching member therewith, a fixed part against which the switching member is abutted on the movements of the actuator, the latter having a further movement beyond the point at which the switching member engages the fixed part, and spring means conditioned by the actuator on the initial part of each movement of the actuator to complete the movement of the switching member, the conducting portion of the actuator constituting part of the circuit of the switch.
9. A switch comprising an insulating supporting body, a rocking pivot carried by the supporting body, a contact electrically connected with said pivot, a push rod extending through the body and provided with manipulating portions and also having insulating and conducting portions, each grooved, a circuit controlling member having a loop to embrace the actuator and also having a slideable connection with said pivot, a second contact co-operative with said circuit controlling member, and a spring having a connection with the switching member adjacent the actuator and also having a loop connection with said pivot.
10. An electric switch comprising a push-rod of conducting and insulating materials, a swinging slideable switching member to be swung by the push-rod, and a spring movable with the switching member and tending constantly to apply a pull to the switching member and at the same time maintaining the switch in operative connection with the push-rod, the push-rod having a dislodgable connection with the switching member and on its movement being adapted to move the switching member against a fixed part to thus disengage the same from the push-rod and the push-rod on each movement thereof tensioning the spring and the tensioned spring when the switching member is thus disengaged from the push-rod, applying a snap to the switching member to cause the switching member to be moved alternately into engagement with the insulating and conducting portions of the actuator.
- In testimony whereof I affix my signature in the presence of two witnesses.
